Primary Examiner — Carol P Rademaker(74) *Attorney, Agent, or Firm* — McAndrews, Held & Malloy, Ltd.(57) **CLAIM**

The ornamental design for an flask, as shown and described.

DESCRIPTION

FIG. 1 is a front, right, top perspective view of my new design for a flask;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a front, left, bottom perspective view thereof.

The gridded line work shown on the perimeter surface edge of the body of the flask and on the side surface of the cap represents a contrasting texture.
